Attorney.

UNITED STATES PATENT OFFICE.

NELSON R. WILLIAMSON, OF PORTLAND, INDIANA.

FOLDABLE SHIPPING BOX.

Application filed December 11, 1925. Serial No. 74,797.

The object of my present invention, broadly speaking, is to provide a collapsible or folding box, which is especially intended for enclosing a burial casket, having means whereby the box can be returned to the sender in folded condition whereby it will occupy but a minimum amount of space, that is it can be returned in K. D. or flat condition, thereby reducing the carrying charges thereon, and having means whereby it can be easily opened and closed by the parties sending or receiving it. The construction as shown is also adapted to retain the goods in secure position within the box, whereby they can not become damaged in shipment, and also providing a construction which can be manufactured and sold at a comparatively low price.

The preferred means for carrying out the principles of my invention in a practical manner is shown in the accompanying two-sheets of drawings, in which—Figure 1 is a side elevation of my box in extended or operative condition. Figure 2 is an elevation of one end of my box. Figure 3 is a cross section, as taken on the line 3—3 of Figure 1. Figure 4 is a longitudinal section, as taken on the line 4—4 of Figure 2. Figure 5 is a perspective view of one of the lid clamping devices. Figure 6 is a plan of a portion of the lid, showing the means for hinging said device thereto. Figure 7 is a perspective view of one portion of said clamping device. Figure 8 is a side view of the box folded. Figure 9 is an end view of the box folded. Figure 10 is a detail of part of one side of one of the corner members, and Figure 11 is the same as taken at right angles thereto. Figure 12 shows a portion of one of the hinged supports. Figure 13 is a cross section of one of the lower corners of the box, showing the hinged support in connection therewith. Figure 14 shows one of the latch members. Figure 15 is a detail showing the catch for the latch member. Figure 16 is a plan view of one of the clamping bars. Figure 17 is a perspective view of the head portion of one of the rods or bars which connect with the said clamping bar. And Figure 18 is a side elevation of the same parts shown in Fig. 17.

Similar indices denote like parts throughout the several views.

In order that the construction, the operation, and the several advantages of my in-

vention may be more fully understood and appreciated I will now take up a detailed description thereof, in which I will set forth the same as comprehensively as I may.

The enclosure, or box, proper comprises two main sides, 1 and 2.

Numeral 3 denotes the bottom. Numeral 4 denotes the top and numerals 5 and 6 denote the two ends of the box.

The sides 1 and 2 do not extend down to the bottom 3 but they rest on the respective side-strips 7 and 8, the former being of less height than the latter, and they are both of the same thickness as are the said sides. The said strips 7 and 8 are rigidly secured to the top surface of the bottom 3, and are located at the edges and extend the full length thereof, with the ends 5 and 6 located therebetween.

The lower edges of each of the ends 5 and 6 are hinged to the surface of the bottom 3 by a pair of hinges, each member of each pair of hinges being denoted by numerals 9 and 10, respectively. The bottom 3 is reinforced by the cleats 11, which extend from end to end thereof, and are located near the edges thereof.

Also, the lid 4 is reinforced by the cleats 12, which extend longitudinally thereof and are the same distance apart as is the distance between the sides 1 and 2, that is they contact with said sides when the lid is in operative position, as in Figs. 1, 2 and 3.

All of said parts are, in this instance, shown as of wood construction, and the remainder of the parts herein mentioned are of metal construction, except the two cross-bars hereinafter described. However I am not to be limited to the materials as described, but various parts may be made of any suitable material as desired.

Each of the corners is protected by an angular metal corner member, as shown in Figs. 10 and 11, which are made on an enlarged scale from that of Figs. 1, 2, 3 and 4. Each of the corner members is denoted by numeral 13, one portion of which contacts with a side, and the wider portion contacts with the ends of the sides and laps over the end members as shown. The lower portion of the corner member is hinged to a foot member 14, by means of a pivot 15. The foot members are secured to the strips 7, and 8, and the bottom 3, and enclose parts thereof as indicated. The

members 13 and 14, secured together by the pivot 15, are arranged alternately with relation to each other at each end of the box, that is the member 14 is on the outside of one and on the inner side of the other; this is in order that the members 13 at one end may pass each other when the box is folded, as in Figs. 8 and 9.

The box thus formed is, in this instance, 10 adapted to contain a burial casket A, shown in dotted lines in Fig. 4.

In order to clamp the casket A in position, and to provide further hinging means for the sides 1 and 2, and to brace the box and 15 provide further strength thereto, I provide the following means, shown most clearly in Figs. 12 and 13, there being one set of such means at each end portion of the box, and each comprises a bar 16, which extends across 20 underneath the bottom 3, with its end portions turned up at right angles, passing up through the bottom 2 and against the inner sides of the strips 7 and 8, each forming a member 17 integral with the bar 16. Numer- 25 al 18 denotes the respective bars secured to the inner faces of the sides 1 and 2, with their lower ends hinged at 19 to the respective members 17, as shown in Fig. 13. The bars 18 extend at angles from near their hinge 30 connection toward the end and the top of the box, and near the upper end of each a slot 20 is formed therethrough and extending parallel therewith, as shown in Fig. 4.

Numeral 21 denotes the connecting rods 35 each having an elongated head 22 on one end, as shown in Fig. 17, which when turned longitudinally thereof will enter the slot 20, and then when the rod is turned parallel with its bar 18 the head will be locked in position 40 therein. The outer portion of the rod 21 is threaded, with a nut 23 adapted to run thereon. The companion of each rod 21 is in the nature of a flat bar 24, but it also has an elongated head 22 formed on one end thereof, 45 but the opposite end thereof is provided with a row of apertures 25, shown in Fig. 4, forming a row parallel with the bar.

At one end of the box there is a rod 21, on one side with a bar 24 at the other side, 50 and the same is true at the other end of the box, that is, there is a rod 21 and a bar 24 on each side of the box.

Numeral 26 denotes the clamping bars, there being two in number, one at each end 55 of the box, as shown in Fig. 4. One end of each clamp-bar is provided with a hook 27 which is adapted to engage in either of the apertures 25. The other end of each clamp-bar 26 has an aperture 28 therethrough to receive the threaded end of a rod 21, with a washer-plate 29 secured around said aperture.

From the above it will be seen that one 60 end of each clamp bar 26 is adapted to be secured by a rod 21 and the other end by a

bar 24, whereby said bars 26 may be clamped tight against the angular upper portions of the ends of the casket A, whereby the casket may be securely clamped in carrying condition.

Formed through the bottom are four, or more, round apertures 30, which are directly above a bottom bar 16, and carried by said bars and extending up through each of said apertures 30 is a pointed spur 31, which spurs extend a short distance above the surface of the bottom 3, as shown. Said spurs are adapted to be forced into the bottom of the casket A, when the casket is resting on the bottom 3, in which position the casket is shown in Fig. 4.

At each corner of the box a notch 32 is formed in the upper edge of the sides 1 and 2, the same being in a line with the inner faces of the ends 5 and 6, as shown in Fig. 35 15. A pin 33 is driven into each end of each of said sides, each of which pins extend through the respective notches 32, and the heads of said pins, and also the outer ends of the notches 32, are covered by the upper 90 portions of the respective corner members 13, as is shown.

In Fig. 14 is shown one of the four latches, one for each corner of the box. Each latch consists of a flat bar 34, pivoted at 35 to the inner faces of the ends 5 and 6. A notch 36 is formed in the lower edge and near the outer end of the bar 34, which notch is adapted to hook over its respective pin 33. Said bars 34, when in securing position, are 100 located even with the upper edges of the ends 5 and 6, by which it will be seen that when the top 4 is in place that it will prevent the latches from swinging upward out of engagement with the pin 33, yet when the lid 105 is removed it will be very easy to turn the latches upward and release the sides from engagement with the ends.

Four or more lid securing devices or clamps are provided in this instance, to hold the lid in place on the body of the box, all of which are identical with that shown in detail in Figs. 5, 6 and 7, which I will now describe: Where each of said clamps is located there are two notches, 35 and 36, formed in the edge of the lid and they are spaced a short distance apart, and a pivot rod 37 extends longitudinally of the lid through both of said notches as shown in Fig. 6, or a separate pivot member may be provided for each notch. A V-shaped member 38 is provided, whose end portions are bent at right angles thereto with the extreme ends forming eyes 39, through which the rod 37 is inserted, whereby the member 38 is pivoted to the lid. The other member of the clamp comprises a substantially U-shaped member having the two arms 40 and 41 which are parallel with each other. The lower ends of said arms terminate in the 139

eyes 42 and 43, respectively, to engage in the respective staples 44 and 45, or similar means which are secured in the sides 2, for instance whereby the U-shaped member is 5 hinged to the side. The upper ends of the arms 40 and 41 are integrally connected by the central member 46 which is turned inward at right angles to the said arms, and it is adapted to engage over the edge of the 10 top 4, as shown in Fig. 5. Screwed into the top of the lid 4 is an angular key 47, which is adapted to engage the free or inner end of the member 38.

In Fig. 5 the clamp is shown in closed or 15 locking condition, whereby the lid is secured in place. Now by giving the key 47 a half turn the member 38 will be released whereby it may be turned outward thereby releasing the member 46 and permitting it to be turned 20 outward and downward, thereby releasing the lid or top 4.

In practice the box is to be opened out as 25 in Figs. 1, 2 and 3, except the lid 4. The casket A is then placed in the box, with the spurs 31 sticking into the bottom thereof, the rods 21 and the bars 24 are then placed in connection with their respective members 18 by inserting the heads 22 in their slots 20 where they will be locked when said 30 rods and bars are brought to operative position, as in Fig. 4. The bars 26 are then placed in position by first inserting the hooks 27 in a suitable aperture 25 of the bars 24, then bringing said bars 26 across 35 the upper angular edges of the casket inserting the threaded ends of the rods 21 in their apertures 20. Now by running the nuts 23 on the rods 21 and then tightening 40 them down into firm contact with their plates 29, the casket will be secured in shipping condition with no danger of its shifting around in transport. The lid is then placed in position, as in Fig. 3, then by closing the clamps as in Fig. 5 the casket 45 will be ready for shipment. After the package has arrived at its destination a reversal of said operation will free the casket and it can then be lifted from the box.

The box may now be placed in condition 50 for return shipment as follows: The lid having been removed by releasing the clamps shown in Fig. 5, the next movement will be to turn the latch bars 34 which will release the ends 5 and 6 from the sides. The 55 ends are then turned inward toward each other to bring them flat on top of the bottom 3. The sides 1 and 2 are then turned inward upon each other on top of the ends. On account of one of the strips, 7 and 8, being 60 wider than the other it is apparent that the two sides may lay flat together without straining the various hinges. The top 4 is then turned upside down and placed on the sides, the bars 26 being placed in 65 the space between ends 5 and 6.

In order to secure the parts together in folded position two bolts, 48 and 49, are employed, as in Figs. 8 and 9. Said bolts are inserted through corresponding holes formed through the top, the sides, the ends and the bottom, and when said bolts are tightened it is apparent that all of said parts will be securely clamped together as shown.

It should be noticed that when shipped 75 extended that the cleats are on the under side and when folded said cleats should be on outside. This makes the package more compact and more particularly it saves changing the shipping directions which are usually attached to the lid. In this arrangement the shipping directions may be 80 permanently placed on the upper and the lower side of the top which will change the directions by simply turning over the lid.

It is to be understood that various changes 85 may be made in the several details herein shown without departing from the spirit of the invention and without sacrificing any of the advantages thereof which are new and useful and which involve invention.

Having now fully shown and described 90 my invention, what I claim and desire to secure by Letters Patent of the United States, is—

1. A shipping box comprising a bottom, 95 ends hinged to the bottom, sides hinged to the bottom, the ends and the sides being adapted to fold inward over and parallel with the bottom, a top cover for the box, means for detachably connecting the sides and the ends together at each corner of the box including latches which are secured by the lid, cleats secured to the lid and contacting with the sides to retain the lid in place, braces extending underneath the bottom and extending upward at angles and secured to the inner faces of the sides of the box, hinges formed in said braces at the lower edges of the sides, coupling means 100 detachably connected with the upper ends of said braces, and a bar connecting each two of said coupling means at each end of the box for securing goods in position in the box.

2. A foldable box including a bottom, 115 strips extending up from the edges of the sides of the bottom, one of said strips being wider than the other, a side member resting on each of said strips and extending upward to the same distance above the bottom, a corner member secured to each end of each of the sides, a foot member hinged to the lower end of each corner member and secured to the bottom and to the ends of said strips, an end member hinged to each end 120 of the bottom and fitting between the ends of the sides, latches for securing the upper portions of the ends and the sides, brace bars extending underneath the bottom and along the inner faces of the sides and hinged 125

at the juncture of the sides with their respective strips, pointed spurs secured to that portion of each brace bar which extends underneath the bottom with said spurs projecting upward through apertures in the bottom to engage the goods located in the box, a lid, clamps for detachably connect-

ing the lid to the upper edges of the sides, means for retaining the lid in alignment with the body of the box, and means for 10 securing goods within the box.

In testimony whereof I have hereunto subscribed my name to this specification.

NELSON R. WILLIAMSON.
